BABY SHOE

Filed May 13, 1929

Inventor:
Louis J. Golden
By
Maurice S. Cayne
Atty.

UNITED STATES PATENT OFFICE

LOUIS J. GOLDEN, OF HIGHLAND PARK, ILLINOIS

BABY SHOE

Application filed May 13, 1929. Serial No. 362,628.

The invention relates to shoes, and more particularly to the class of baby or infant shoes.

Before an infant begins to walk it generally assumes either a lying or sitting position. When in either of these positions, it will be noted that the shoes worn by the infant will have main points of contact with the infant's foot at the heel portion of the shoe, also at the portion directly above the ankle, as well as at the instep portion of the shoe. Heretofore, it has been the practice to construct an infant shoe in a manner similar to that employed in the construction of shoes for adults, resulting in comparatively heavy seam lines, as well as several plies of leather at the points of the shoe where the main contacts, hereinabove mentioned, with the foot of the infant occur. Thus, the infant shoes, as constructed heretofore, have been improper and often result in inconvenience and discomfort to the wearer.

It is the main object of this invention to construct an infant shoe wherein the objections above set forth will be overcome, in that the shoe will have no seam lines and only a single ply of leather at the points where the greatest contact with the shoe of the wearer is present.

Another object of this invention is to provide a shoe of the character described, wherein in the foot of the wearer can be readily and quickly inserted therein and removed therefrom, and when secured in place on the foot cannot be kicked off or lost therefrom.

Another object of this invention is to provide a shoe of the character described, which will be composed of few and simple parts which may be readily and easily assembled, on lines convenient for low-cost manufacturing, and which will be snug and comfortable, as well as further providing a shoe having a neat and attractive appearance.

A further object of this invention is to provide a shoe of the character described, having a novel and improved design of upper, whereby the usual means of fastening the same on the foot, such as buttons, or the like, is eliminated.

A still further object of this invention is

to provide a shoe of the character described, the upper of which may be made up of few and simple parts assembled so as to eliminate the usual front medial seam and the heel portion of which may also be made up in such a manner as to eliminate the usual rear medial seam, and which is adapted to be readily and easily placed on the foot of the wearer, and which may be readily and quickly secured on the foot of the wearer without causing any discomfort to the wearer when so secured.

A still further object of the invention is to provide a shoe of the character described, comprising front and rear uppers, said uppers being connected to each other on the opposite side seam lines at their lower portions, thereby eliminating the usual front and rear medial seams, the upper portion of said rear upper being inclined rearwardly to more readily accommodate the ankle of the wearer when the latter is in a lying or sitting position.

A still further object of this invention is to provide a shoe of the character described, comprising front and rear uppers, said uppers being connected to each other on opposite side seam lines at their lower portions, the heel portion of said rear upper being cut out and closed by a suitably shaped insert secured to said rear upper on opposite side seam lines, whereby the usual rear medial seam is eliminated.

With the foregoing and other objects in view, which will appear as the description proceeds, the invention consists in certain novel features of construction, arrangements, and combination of parts, hereinafter more fully described, illustrated in the accompanying drawings and particularly pointed out in the appended claims; it being understood that various changes in the form, proportion, size and minor details of the structure may be made without departing from the spirit or sacrificing any of the advantages of the invention.

Stated generally, the invention comprises an infant shoe, the upper of which is made up of few and simple parts which, when assembled, form a shoe which is not only snug and comfortable fitting, but also has a very

neat and attractive appearance. The upper comprises a rear portion having a vertical slit at its lower end for forming when in assembled position, an inverted V-shaped cut-out the side edges of which, when in assembled position, extend to a point adjacent the shank portion of the shoe and vamp portion which is secured to said rear portion by oppositely disposed side seam lines, an upper front portion which is also provided with an inverted V-shaped cut-out at the lower portion thereof, and is secured to said vamp portion by substantially horizontally disposed seam lines, an insert for completely closing the front of said shoe and a rear insert secured to said rear portion on side seam lines for completely closing the heel portion of the shoe.

The major portions of said rear and upper front portions have their side edges in overlapping relation and are provided with suitable fastening means, such as straps, or the like, adapted for pulling the shoe upper snugly around the ankle of the wearer to securely hold the shoe on the foot, whereby the same may not be kicked off or lost therefrom.

For the purpose of facilitating an understanding of my invention I have illustrated in the accompanying drawings a preferred embodiment thereof, from an inspection of which, when considered in connection with the following description, my invention, its mode of construction, and many of its advantages, should be readily understood and appreciated. Referring to the drawings, in which similar characters of reference are employed to indicate corresponding parts throughout the several figures of the drawings:

Figure 1, is a diagrammatic or plan view of the rear portion of the upper of a shoe embodying the invention;

Figure 2, is a diagrammatic or plan view of the vamp portion of the same;

Figure 3, is a diagrammatic or plan view of the front upper portion of the same;

Figure 4, is a diagrammatic or plan view for an insert for the vamp portion of the shoe;

Figure 5, is a diagrammatic or plan view for an insert for the heel portion of the shoe;

Figure 6, is a view in perspective of the completed assembly of the shoe embodying the invention;

Figure 7, is a detail view taken on line 7—7 of Figure 6.

Referring to the drawings more specifically by characters of reference, the numeral 10, designates the rear upper, which is formed from a single piece of leather and is provided with a slit 11, at the lower portion thereof. The said rear upper 10, is formed to provide the side edges 12, and lower edges 13, and the substantially rounded upper edge, as shown in the drawings, for providing a neat appearance when in assembled position.

The forward vamp portion 14, of the upper of the shoe is cut in the form shown in Figure 2, of the drawings, said vamp portion being in a single piece and is sewed to the lower side edges 12, of the rear upper 10, on opposite side seam lines 15, and to the bottom edge of the front upper 16, on the angularly disposed seam lines 17. The front upper 16, is rounded at its top edge, as shown in the drawings, so as to present a neat appearance when in assembled position, and the side edges of said front upper are adapted, when assembled, to overlap the said side edges of the rear upper 10, as shown in Figure 6. The lowermost edge of the front upper 16, is cut substantially straight, and the said upper is provided at the lowermost portion thereof with a longitudinal slit 18, adapted to form a cut-out, said cut-out extending from the lower edge of said upper to a point intermediate the ends thereof, as shown in Figure 3. When the said front upper is assembled, the lower edges thereof are turned up a slight amount to open up the slit 18, and to permit the said lower edges to be sewed to the vamp portion 14, along the same lines 17, as shown in Figure 6.

To completely close the front portion of the upper of the shoe, an insert 19, is provided, said insert being cut in the desired shape, as shown in Figure 4, and is secured to the vamp portion 14, and front upper 16, on the seam lines 20, 21, and 22, the latter two seam lines extending along the sides 106 of the slit 18, which slit assumes the shape of an inverted V when in assembled position, as clearly shown in Figure 6.

The opening formed in the heel portion of the shoe because of the slit 11, provided in the rear upper 10, is adapted to be closed by an insert 23, said insert being cut in the desired shape, as shown in Figure 5, and is secured to the rear upper 10, on the seam lines 24; the said seam lines extending along the sides of the slit 11.

It will be noted that in order to provide for the maximum comfort at the heel portion of the foot the insert 23, is cut full, so as to provide the outward bulge, as shown at 115 25, Figure 6, when the shoe is in fully assembled position. This feature of construction assures a sufficient amount of space for receiving the heel portion of the foot. It will also be noted that the uppermost portion of the rear upper inclines rearwardly and upwardly, as shown at 26, in Figure 6, to prevent the said portion of the rear upper from binding the ankle of the wearer, when the latter is in a sitting position. It 125 has been estimated that in order to give the maximum amount of comfort this rear portion should incline rearwardly at an angle of approximately twenty-five degrees from the vertical. By constructing the rear por-

tion of the shoe in this manner it is possible to provide for a maximum of comfort to the wearer of the shoe, regardless whether it is in a lying or sitting position.

5 In order to eliminate any possibility of the formation of any irregularities or rough places in the heel portion of the shoe the insert 23, is stitched to the rear upper 10, in such a manner as to provide a perfectly smooth inner surface at the point of the stitching or seam lines. This may be accomplished by tapering or beveling the side edges of the cut-out 11, in the rear upper 10, as more clearly shown at 27, in Figure 7, of the 10 drawings. By reason of this construction a perfectly smooth inner surface is provided at the rear of the shoe. If desired, however, the said insert may be stitched to the rear upper 10, in the usual and well known manner, as even then the heel portion of the shoe 15 will still be perfectly smooth, the seam lines 24, connecting the insert 23, to the rear upper 24, being positioned on side portions of the heel, the point of main contact still remaining 20 perfectly smooth.

The straps 28, and 29, are provided for securely holding the shoe in place on the foot of the wearer. The upper strap 28, is adapted to extend through a horizontally disposed 30 row of vertical slits 30, provided in both the front and rear uppers. The lower strap 29, is secured at the rear portion of the shoe by means of the stitching 24, the forward portion of said strap extending through vertical strips provided therefor in the front upper 16. Suitable fastening means, such for example, as the buckles 31, are provided on said straps 28, and 29. Obviously, any 35 other suitable fastening means may be employed, such for example, as suitable lacing extending around the ankle portion of the shoe, or the like.

It will be noted that the upper of the shoe is adapted to extend well around the ankle of the wearer and that it may be secured around the ankle by fastening the ends of the straps 28, and 29. The sides of the shoe upper, it will be observed, are adapted to fit loosely around the ankle of the wearer, and 40 may be drawn around the ankle to the desired comfort of the wearer. In any event, it will be noted, that the uppermost rear portion of the upper inclines rearwardly and upwardly so as to eliminate the possibility 45 of any binding effect around the ankle, regardless of what position the wearer may assume. It will also be noted that by the above construction the rear, as well as the front, medial seams are eliminated, and a 50 very neat and attractive, as well as comfortable and snug fitting shoe is obtained. Also, because of the peculiar side construction of the upper, the foot of the wearer can be readily and easily inserted therein and removed 55 therefrom, and when secured in place on the

foot cannot be kicked off or lost therefrom, because of the fastening means around the ankle portion of the shoe. It will also be noted that the usual button and button-hole fastening means are eliminated, whereby a 70 much simpler and economical construction is obtained.

75 The essential novelty of the construction, as here shown, consists in a peculiar cutting of the parts which go to make up the upper of the shoe for effecting the contour of the front of the shoe, as well as the heel portion thereof, the said front and heel portions being completed by the inserts 19, and 23. The resulting design is very neat in appearance and highly meritorious from the stand-point of comfort and utility.

80 It is believed that my invention, its mode of construction, and many of its advantages, should be readily understood from the foregoing without further description, and should also be manifest that while a preferred embodiment of the invention has been 85 shown and described for illustrative purposes the structural details are, nevertheless, 90 capable of wide variation within the purview of my invention, as defined in the appended claims.

95 What I claim and desire to secure by Letters Patent of the United States is:—

1. A shoe of the character described, including front and rear upper portions and a vamp portion, said rear portion joined to said vamp portion on opposite seam lines, said front portion joined to said vamp portion on angularly disposed seam lines, said front and vamp portions having cut-outs provided therein, said cut-outs forming a front opening, an insert for closing said opening, a slit provided in said rear portion, and an 100 insert for closing the opening formed by said last mentioned slit.

105 2. A shoe of the character described, including front and rear upper portions and a vamp portion, said rear portion having a slit provided therein at the lower portion thereof, adapted to form a cut-out, said front and vamp portions having cut-outs provided therein, said cut-outs forming front and rear 110 openings and suitable inserts for closing said openings, all of said parts being joined so as to eliminate any front or rear medial seam lines.

115 3. A shoe of the character described, including front and rear upper portions and a vamp portion, said rear portion joined to said vamp portion on opposite seam lines, said front portion being provided with a slit adapted to form an inverted V-shaped 120 cut-out at the lower portion thereof, the lowermost edges of said front portion being joined to said vamp portion, a substantially circular cut-out provided in the said vamp portion, an insert joined to said vamp and 125 front portions for closing the said cut-outs,

and a slit adapted to form a substantially inverted V-shaped cut-out being provided in said rear portion at the lower edge thereof, and an insert joined to said rear portion on side seam lines for closing said last mentioned cut-out.

4. A shoe of the character described, comprising front and rear upper portions and a vamp portion, an insert for said front portion, a second insert for said rear portion, all of said portions being joined together to form a shoe upper having no medial front or rear seam lines.

5. A shoe of the character described, comprising front and rear upper portions and a vamp portion, cut-outs provided in said front and vamp portions, said cut-outs forming a front opening, an insert for closing said opening, a slit provided in said rear portion, adapted to form a cut-out, an insert for closing said cut-out joined to said rear portion on side seam lines, and means for securing said portions together, whereby the necessity for front and rear medial lines is obviated.

6. A shoe of the character described, comprising rear and front upper portions and a vamp portion, cut-outs provided in said front and vamp portions, said cut-outs forming a front opening at the instep portion of the shoe; an insert for closing said front opening, a slit provided in the rear upper portion at the lower edge thereof, adapted to form a cut-out, said cut-out forming an opening of the heel portion of the shoe, an insert for closing said opening, said insert being joined to said rear upper on side seam lines, the portion of said rear upper extending above said insert when in assembled position being formed to incline rearwardly and upwardly, and fastening means adapted to draw the said upper portions around the ankle of the wearer for securing the shoe in place on the foot.

In testimony whereof, I affix my signature.

LOUIS J. GOLDEN.
